UNITED STATES PATENT OFFICE.

DAVID BUZZELL, OF CHARLESTOWN, MASSACHUSETTS.

RAILROAD-CAR SEAT.

Specification of Letters Patent No. 19,910, dated April 13, 1858.

To all whom it may concern:

Be it known that I, DAVID BUZZELL, of Charlestown, in the county of Middlesex and State of Massachusetts, have invented **5** a new and useful Railway-Car Seat or Recumbent Chair; and I do hereby declare that the same is fully described and represented in the following specification and the accompanying drawings, of which—

10 Figure 1, denotes a side elevation. Fig. 2, a front elevation; Fig. 3, a vertical, central and longitudinal section of such car seat or chair. Fig. 4, is a view of the operating mechanism within the reversible back to be **15** hereinafter described. Fig. 5, is a top view of the railway car chair.

Like many railway car chairs, mine is furnished with a reversible back, that is one, which can be turned over from front **20** to rear of the bottom or seat part of the chair, or from rear to front thereof, in order that a sitter may face either in one direction or the opposite as circumstances or convenience may require.

25 In the drawings A, represents the reversible back; B, the seat of the chair; and C, C, the supporting frame or arm rest standards which are affixed to the floor and connected by a cross bar D, arranged below the seat **30** as seen in Fig. 3. With this seat B, or with it and the reversible back A, are combined two foot rests E, F, by mechanism to be hereinafter described.

Each foot rest is supported by the lower **35** legs of two levers G, G; G', G', which turn on fulcra or pins projecting from the inner sides of the standards, C, C, such pins or fulcra being shown by dotted lines at a, a, in Figs. 1, and 3. These levers also serve to **40** support the seat B, and by means of round pins or journals b, extended from the opposite sides of the seat and into the levers in the positions shown by dotted lines in Fig. 3.

45 Fig. 6, is a side view of one of the levers G, and exhibits the pin holes and fulcrum hole thereof. Each of these levers, in advance of its fulcrum, is jointed to one of two rocker levers or lever frames H, each **50** of which is arranged and made to turn upon a fulcrum c, as shown in Figs. 2, and 3, such fulcrum being extended from the standard C, within and against which such lever is placed. Above the fulcrum, each rocker **55** lever H, is jointed to one of two connecting

links or bars I, I, which are also jointed to opposite edges of and at the middle of the reversible back A. Each corner of the seat B, is furnished with a round projection d, to enter a corresponding socket piece e, fixed **60** to the reversible back, there being one of the said socket pieces at each corner thereof, as shown in the drawings. By means of such devices, the back may be connected with the seat or readily disconnected therefrom as circumstances may require, such connections operating in other respects as hinges, so that while a person is sitting upon the seat and throws or forces his body against the back, he may incline the back **65** and at the same time move the seat forward and elevate the foot rest, thus imparting to the back, seat and foot rest of the chair, recumbent or convenient positions for the repose or ease of the sitter. While the back is **70** being pressed backward, the lever frames H, H, will be turned on their fulcra so as to throw forward, or in one direction, the lower legs of all the levers G, G; G', G'. In consequence of this, both of the foot rests will **75** be moved forward or in one direction, at one and the same time. By this moving forward the rearmost foot rest it will be carried more out of the way of the feet of a sitter, who may be in a chair that may be arranged **80** in rear of the chair to which the said foot rest may belong.

Each foot rest consists of two boards f, and g, one being hinged to the other at or near two of their edges and so applied or **85** made with respect to the other as to be capable of being turned down into a right angle or thereabout with it and held in such position by abutting against it or a suitable stop. The part g, at or near the **90** middle or each end of it has journals h, h, projecting from it and turning in the two adjacent levers G, G'. At some distance below each of the said journals, each of the **95** said levers is furnished with a projection or stop i, against which the back board g, of the foot rest abuts, or is estopped when turned so as to bring the front board either in front or in rear of it. The sectional view, Fig. 3, not only represents one foot **100** board as turned down in a position to receive the feet of a sitter, but shows the other foot board as reversed or turned over. By such a construction of each foot board, it **105** may be turned over or reversed so as to **110**

bring its foot rest *f*, when underneath the bottom of the chair more out of the way of a sitter in rear of the chair, than would be the case, were it not constructed so as to be 5 reversible as described.

The reversible back *A*, I make in three parts *k*, *l*, *m*, the two parts *k*, and *m*, being what may be termed head rests and so applied to the middle part *l*, as to be capable of 10 being moved toward or from the same, that is to say, each part *k*, or *m*, is supported by two sliders *n*, *n*, which slide into the middle part *l*, and have arranged between and against them, two helical springs *o*, *o*, as 15 shown in Fig. 4. The sliders move in opposite directions through the middle part, *l*, so that while either head rest is supported by the seat of the chair or by its latches, it will support the springs and the other head 20 rest bearing upon them. These springs serve for both head rests and to elevate the uppermost head rest to such a height above the middle part *l*, as may be most convenient for the support of the head of a sitter. 25 Each head rest, is provided with two or any other suitable number of latches *p*, *p*, for holding it in position at such distance from the middle part *l*, as occasion may require, such latches being operated by a thumb lever 30 *r*, or, *s*, arranged on one edge of the middle piece, *l*, and connected with the latches by suitable connections or rods, *t*, *t*, *t*, as shown in Fig. 4. The latches operate with notches *u*, *u*, *u*, made in the sliders. 35 From the above, it will be perceived, that the upper head rest may be lowered down below the neck of a sitter or it may be elevated to a suitable height to give support to his head; also, that in whatever direction, 40 the back may be turned, that is whether it may be made to rest on the front or the rear of the seat, one head rest will be above the part *l*, and the other below it, the lowermost head rest under such circumstances contrib- 45 uting with the part *l*, to support the back of the sitter.

The act of forcing rearward or inclining

the back of the chair, at the same time, will cause the front foot rest to be elevated.

I am aware, that it is not new to make a 50 recumbent chair in such manner, that the back, when moved rearward shall throw up an apron or foot rest, such having been accomplished by applying the foot rest to two levers and connecting the said levers to the 55 back by jointed arm rests such being represented in the patent granted by the Government of the United States to J. G. Holmes September 24th, 1844.

My mode or mechanism for effecting the 60 elevation of the foot rests by the rearward movement of the back of the chair differs from others as above set forth, inasmuch as its two foot rest levers *G*, *G'*, are connected with the connecting bars *I*, *I*, by two intervening rocker levers *H*, *H'*, such levers, as 65 shown in the drawings, being equivalent to what are usually termed tri-armed levers, as they are intended to operate all four of the levers *G*, *G*, *G'*, *G'*, of the two foot rests 70 at one and the same time as above described.

What I claim is—

1. An improved railway chair or combination of a stationary seat, a reversible back, two swinging foot rests and mechanism so 75 connecting the said foot rests and the reversible back, as to enable the foot rests to be operated by the back in manner and under circumstances substantially as described.

2. I also claim making the reversible back 80 *A*, in three parts *k*, *l*, *m*, arranged and applied together substantially in manner and so as to operate as specified.

3. I also claim the application of the 85 springs to the head rests in the manner set forth, such head rests being provided with latches or their equivalents as specified.

In testimony whereof I have hereunto set my signature this 30th day of November 1857.

DAVID BUZZELL.
